(57) CLAIM

I claim the ornamental design for a storage rack, as shown and described.

DESCRIPTION

FIG. 1 is a front view of the new ornamental storage rack of the present invention;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a front right perspective view thereof; and,

FIG. 8 is a left back perspective view thereof.
